UNITED STATES PATENT OFFICE.

MICHAEL CIULLA, OF HASTINGS UPON HUDSON, AND DOMENICO P. FONTANA, OF NEW YORK, N. Y.; SAID CIULLA ASSIGNOR OF HIS ENTIRE RIGHT TO SAID FONTANA.

PIPE TAMPER.

Application filed August 23, 1923. Serial No. 659,009.

To all whom it may concern:

Be it known that we, MICHAEL CIULLA, a subject of the King of Italy, and a resident of Hastings upon Hudson, in the county of 5 Westchester and State of New York, and DOMENICO P. FONTANA, a subject of the King of Italy, and a resident of the city of New York, borough of Manhattan, in the county and State of New York, have invented a new and Improved Pipe Tamper, 10 of which the following is a full, clear, and exact description.

This invention has relation to smoker's pipes and has reference more particularly to 15 an attachment therefor constituting means for tamping or packing the tobacco into the bowl of the pipe.

It has been observed that pipe smokers are constantly burning or soiling their fingers by attempting to tamp or pack the tobacco into the bowl of the pipe or are subjected to the annoyance of having to search for a suitable implement to perform this function.

25 It is therefore an object of the present invention to provide a tamping or packing implement which will constitute an attachment for the pipe and which includes means for readily associating or disassociating the 30 implement therefrom whereby said implement will always be within convenient reach.

As a further object of the invention contemplates an attachment of the character set forth which is extremely simple in its 35 construction, inexpensive to manufacture and apply and which is highly efficient in its purpose.

With the above recited and other objects in view, the invention resides in the novel 40 construction set forth in the following specification, particularly pointed out in the appended claim and illustrated in the accompanying drawings, it being understood that the right is reserved to embodiments 45 other than those actually illustrated herein to the full extent indicated by the general meaning of the terms in which the claim is expressed.

In the drawings—

50 Figure 1 is a perspective view of a pipe

equipped with an attachment constructed in accordance with the invention.

Fig. 2 is a fragmentary side elevation with parts in section and illustrating respectively in full and dotted lines the 55 tamper in use and in its applied position when not in use.

Referring to the drawings by characters of reference, A designates the bowl of a pipe provided with the usual integral stem 60 portion B and removable mouth piece C.

The attachment constituting the invention consists of a keeper plate 10 of substantially circular configuration which is attached by screws or other fastening elements 65 11 to the rear side of the bowl A. The plate is provided with peripheral inwardly bent hooks 12 substantially at diametrically opposite points of the side of the plate and one of which is arranged at the top thereof. On the upper side of the stem portion B a socket element 13 is embedded. The tamper or packing implement comprises a substantially circular head 14 which conforms in 70 size and shape to the keeper plate 10 and is 75 designed to be associated therewith by sliding the same upwardly with its peripheral edge received by the hooks 12. The tamper or implement is further provided with a handle or shank 15 which is hingedly connected as at 16 to the head 14 adjacent the periphery thereof, the said stem or shank 15 being provided adjacent its free end with a pintle 17 which is designed to be snapped or frictionally received by the socket element 13. 80

In practice the head 14 of the tamper or implement is interengaged with the hooks 12 of the keeper plate 10 after which the shank or handle 15 is swung downwardly 90 to permit the interengagement of the pintle 17 in the socket element 13 whereby said implement when not in use is associated with the pipe and is always in convenient reach when necessary. When it is desired 95 to withdraw the tamper or implement for packing or tamping the tobacco into the bowl of the pipe as illustrated in Fig. 2, the free end of the shank or handle 15 is lifted upwardly to disengage the pintle 17 100

from the socket 13, after which the head 14 may be readily disengaged from the hooks 12 on the keeper plate 10. The head 14 is then swung at substantially a right angle 5 to the shank or handle 15 for use.

We claim:

The combination with a pipe, of an attachment therefor comprising a tamper including a head and a pivoted handle, a 10 keeper secured to the pipe bowl having

means for slidably receiving the head of the tamper, a socket element embedded in the stem portion of the pipe, and a pintle at the free end of the handle for engagement within the socket element to maintain the head positioned in the keeper and whereby to permit of disassociation of the implement for use.

MICHAEL CIULLA.
DOMENICO P. FONTANA.
